UNITED STATES PATENT OFFICE.

ERNEST ARGO, OF ST. LOUIS, MISSOURI, ASSIGNOR TO LA CLEDE-CHRISTY CLAY PRODUCTS CO., OF ST. LOUIS, MISSOURI, A CORPORATION OF MISSOURI.

INTERLOCKING SEWER-TILE.

1,264,138.

Specification of Letters Patent. Patented Apr. 30, 1918.

Application filed August 28, 1916. Serial No. 117,299.

To all whom it may concern:

Be it known that I, ERNEST ARGO, a citizen of the United States, residing at St. Louis, in the county of St. Louis and State 5 of Missouri, have invented certain new and useful Improvements in Interlocking Sewer-Tiles, of which the following is a specification.

This invention relates to interlocking 10 sewer tile and has for its object to provide sewer tile of a nature which will reduce the cost of sewer construction while increasing the strength and ease of assembly. This and other objects will be more fully set 15 forth and shown in the following specification and accompanying drawing;

In which—

Figure 1 is a vertical transverse section 20 through a segment of the sewer constructed of my tile;

Fig. 2 is a perspective of one of the tile;

Fig. 3 is a perspective of a lining tile; and

Fig. 4 is a view similar to Fig. 1 of a 25 modified form.

Like numerals refer to like elements throughout the drawing, in which 10 designates generally an exterior or locking tile, and 11 designates an interior or lining tile.

30 The latter is provided with the upstanding lugs or block portions 11^a preferably having their sides radially converging as shown in Fig. 1, for example, these lugs being cored or apertured as indicated by 11^b for lightness.

The exterior tiles 10 are provided with channels or grooves 10^a, the sides thereof also converging radially, and spaced apart at the inner surface of the tile a distance 40 sufficient to permit insertion therethrough of the lugs or ribs 11^a of the lining tile 11. The exterior blocks 10 are also cored or apertured at 10^b to obtain lightness without sacrificing strength thereof. The blocks

45 10 are shown as provided with two grooves each, the same being formed by the side lugs 10^c and central lug 10^d. The lining tiles 11 are also provided with two or more of the lugs 11^a. When the two sets of tile 50 are assembled to form the sewer they are preferably interlocked as shown in Fig. 1, wherein the lining tile 11 bridges the gap

between adjacent exterior or locking tiles 10, one of the lugs 11^a being contained in a groove 10^a of one of the locking tile and 55 the other lug 11^a being contained in the groove 10^a of the adjacent locking tile 10.

The lining tiles 11 have their sides projecting outwardly of the lugs 11^a as indicated by numeral 11^c, and these side projecting portions lie adjacent corresponding portions of the adjacent lining tiles when in assembled relation, so that when the sewer has been formed on the necessary molds or forms, the latter may be removed without 65 the sewer collapsing, owing to the contact of the sides of the lining tiles 11 and their interlocked engagement with the locking tiles 10. In this way the weight of the 70 sewer is distributed about its internal periphery. In constructing the sewer, however, to prevent leakage and to eliminate cracks, I lay the tile, both courses, in cement, thereby assuring against their displacement and presenting a smooth interior 75 surface, the surface of the lining tile being preferably glazed or otherwise smoothed.

Tapering or divergence of the lugs and the grooves, while not preventing their being easily superimposed in assembling the 80 sewer course, will present a wedging action when the cement surrounding the lugs has set, making a true interlocking construction and eliminating any danger of the collapse or falling apart of the sewer members. 85 At the same time, the tile members may be readily assembled and laid, since it is only necessary in constructing the lower course of the sewer to lay mortar in the grooves and drop the inner ring members into such 90 grooves pressing them firmly home, which will result in the proper distribution and spreading of the cement or other binder. In laying the upper half of the course, cement may be easily spread along the top of the 95 lugs and the outer ring members dropped thereover and pressed firmly home which will also result in the proper spreading and distribution of the cement, the laying of both upper and lower portions being easy 100 and taking comparatively little time, a feature of much merit in my construction.

A tile constructed according to my invention will not only function as a lining as in

present day sewer construction, but also present a course which is of length substantially equal to that of the locking tile while not presenting the weight thereof.

5 The locking tile, as is obvious, will lock the lining tile against displacement in addition to serving as an added strengthening course.

In addition to the above advantages, my 10 improved lining tile presents an increased bearing surface on the locking tile, since the lugs 11^a not only act as locking or engaging members but they present increased contact or bearing surface to the complementary 15 exterior tile 10.

In Fig. 4 I have shown a slight modification wherein the inner tiles 11' have their projecting sides 11^c enlarged thereby presenting an increased contact surface at the 20 sides where the same is necessary and advisable. In this modified construction the central lugs 10^d of the locking tile 10 are grooved or indented as indicated by numerals 10^e to provide for the enlarged 25 sides of the locking tile 11'.

It will be obvious that my invention is susceptible to many modifications and improvements, and I do not wish to be re-

stricted to the form shown and described except as defined in the appended claim.

What I claim is:

A sewer course or the like comprising an inner ring and an outer ring of block members, said inner ring members being constructed with lugs outwardly projecting from their outer surface, the sides of said lugs diverging outwardly from said ring members, said outer ring members being provided with grooves converging inwardly of the bottom thereof, said lugs and grooves being so constructed and arranged that the blocks of one ring may be readily dropped on the blocks of the other ring, said lugs and grooves interfitting in such wise as to provide cement spaces in said grooves surrounding said lugs whereby when cement or the like is set in such spaces a wedging action will be exerted between said lugs and grooves to lock said inner and outer blocks in assembled relation.

In testimony whereof, I have subscribed my name.

ERNEST ARGO.
